UNITED STATES PATENT OFFICE

162,214

ASH TRAY

Leo E. Ohlander, Washington, D. C.

Application July 5, 1950, Serial No. 10,965

Term of patent 14 years

(Cl. D85—2)

To all whom it may concern:

Be it known that I, Leo E. Ohlander, a citizen of the United States of America, residing at Washington, District of Columbia, have invented a new, original, and ornamental Design for an Ash Tray, of which the following is a specification, reference being had to the accompanying drawing, forming part thereof.

Figure 1 is a perspective view of an ash tray, showing my new design.

Fig. 2 is an end elevational view thereof.

Fig. 3 is a sectional view taken on line 3—3 of Fig. 1.

I claim:

The ornamental design for an ash tray, as shown.

LEO E. OHLANDER.
